Primary Examiner — Calvin E Vansant*Assistant Examiner* — Benjamin L. Gray(74) *Attorney, Agent, or Firm* — Neugeboren O' Dowd PC(57) **CLAIM**

The ornamental design for a frame lashing rail, as shown and described.

DESCRIPTION

FIG. 1 is a front perspective view of a frame lashing rail; FIG. 2 is a front elevation view of a frame lashing rail; FIG. 3 is a rear elevation view of a frame lashing rail; FIG. 4 is a right side view of a frame lashing rail; FIG. 5 is a left side view of a frame lashing rail; FIG. 6 is a top view of a frame lashing rail; FIG. 7 is a bottom view of a frame lashing rail; and, FIG. 8 is a rear perspective view of a frame lashing rail. The shade lines in the Figures show contour and not surface ornamentation. The broken lines showing portions of the design in all figures are included for the purpose of illustrating environment and do not form a part of the claimed design.

1 Claim, 5 Drawing Sheets(56)
